UNITED STATES PATENT OFFICE.

ARTHUR C. WHEELOCK, OF OAKLAND, CALIFORNIA, ASSIGNOR TO AMERICAN AUTOMATIC LOCK AND LIFT COMPANY, OF SAN FRANCISCO, CALIFORNIA, A CORPORATION OF CALIFORNIA.

SASH LOCKING AND BALANCING MECHANISM.

1,422,399.

Specification of Letters Patent.

Patented July 11, 1922.

Application filed November 29, 1920. Serial No. 426,899.

To all whom it may concern:

Be it known that I, ARTHUR C. WHEELOCK, a citizen of the United States, and a resident of Oakland, county of Alameda, and State 5 of California, have invented a certain new and useful Sash Locking and Balancing Mechanism, of which the following is a specification.

My invention relates to means for locking 10 a slideable sash in its various positions in the window frame and relates more particularly to the incorporation of said means in connection with mechanism for balancing the sash.

15 An object of the invention is to provide locking means for a slideable sash whereby the latter may be locked in any position it may assume.

Another object of the invention is to provide 20 locking means of the above described type in connection with spring actuated balancing means.

A further object of the invention is to provide 25 means whereby the cooperating members of the locking and balancing mechanism arranged on the window frame and sash may be maintained in the proper relation notwithstanding the usual contraction and distortion of the frame and sash occasioned by the setting and ageing of the structure.

The invention possesses other objects and 30 features of advantage, some of which, with the foregoing, will be set forth in the following description of the preferred form of my invention which is illustrated in the drawings accompanying and forming part of the specification. It is to be understood that I do not limit myself to the showing 35 made by the said drawings and description, as I may adopt variations of the preferred form within the scope of my invention as set forth in the claims.

Referring to said drawings:

40 Figure 1 is a side elevation of the mechanism of my invention with the cover plate removed, parts of the adjacent structure being broken away and shown in section to show the construction more clearly.

45 Figure 2 is a vertical sectional view of the

mechanism, the plane of section being indicated by the line 2—2 of Figure 2.

Figure 3 is a fragmentary side view of a slightly modified form of the device.

Figure 4 is a vertical section taken on the 55 line 4—4 of Figure 3.

Briefly expressed my invention as here embodied comprises a gear or ratchet wheel 60 engaging a rack on the sash and connected to the sash balancing means. Locking means are provided in the form of a plurality of tumblers which are adapted to simultaneously engage the ratchet wheel and are so arranged that during said engagement at least one of the tumblers will invariably be seated 65 in a space between the ratchet teeth, thereby locking the wheel and consequently the sash. Means are provided for holding said tumblers disengaged from the ratchet so that the balancing mechanism may function and 70 the sash may be moved. Means are also included for adjusting the position of the gear or ratchet so that its engagement with the rack may remain unimpaired in case the distance between the side of the sash and the 75 frame is subsequently altered.

A detailed description of the present form of my invention follows:

The mechanism comprises a side plate 2 conveniently attached by screws 3 to the window frame 4. Extending through a slot 6 in the plate 2 is a gear or ratchet wheel 7 which is adapted to mesh with a rack 8 extending longitudinally of and fixed to the sash 9 slidably mounted in the frame 4. 80 The ratchet wheel 7 is rotatably mounted in a casing 11 which is connected to the plate 2 by means of the pivot stud 12 whose axis is parallel to that of the shaft 13 upon which the ratchet wheel 7 is mounted. The casing 85 is provided with a removable cover 14 and is further connected to the plate 2 by a screw 15 whose head 16 engages loosely in a countersunk aperture 17 while the shank engages the tapped aperture 18 provided in an ear 19 90 preferably formed integral with the casing. The head 16 of the screw is held against the plate by a comparatively heavy coil spring 21, thereby normally maintaining the casing 95 and consequently the ratchet wheel 7 in 100

rigid position. From the foregoing it will be readily understood that rotation of the screw 15 will cause the ratchet wheel to move toward or from the rack 8 of the sash. In 5 this manner should the distance between the adjacent sides of the frame and sash become altered for one reason or another whereby the engagement of the ratchet wheel and rack is impaired, it is merely necessary to manipulate the readily accessible screw 15 to enable the wheel to resume the desired engagement.

Preferably fixed at its opposite ends 22 and 23 to the casing and shaft 13 respectively 10 is a spring 24 which is arranged to counter-balance the weight of the sash so that the movement of the latter may be readily controlled in either direction. In the present form of the invention the spring 24 is adapted to be placed in such tension during the movement of the sash in one direction that the sash when released will move back in the opposite direction.

Partly in accordance with the foregoing 15 means are provided for locking the wheel 7 and consequently the sash, in any position in which they may have happened to stop. Heretofore as far as I am aware, when the pawl and ratchet principle was used for 20 locking the sash, a position was very frequently assumed by the sash in which none of the pawls were engaged in any of the slots or spaces of the ratchet but rested directly upon a tooth thereof—in which position 25 the sash was obviously unlocked. Therefore such a situation necessitated a further movement of the sash in one direction or another in order that the pawl could seat in a space. However it frequently happened 30 that the above situation occurred when the sash assumed one of its extreme end positions, thus making it impossible to lock the sash therein. In accordance with my invention 35 the foregoing is eliminated since a pawl or tumbler is arranged to invariably engage one of the ratchet spaces. Preferably 40 slidably mounted in depressions 26 and 27 in the extension 28 of the casing are tumblers 30 and 31 respectively, which as here 45 shown are corradially disposed with respect to the ratchet wheel and spaced circumferentially at the pitch circle thereof a distance equal to approximately one and one-half times the pitch. Encircling the rear end of 50 the tumblers are coiled springs 32 and 33 which are adapted to normally hold the tumblers in engagement with the toothed face of 55 the ratchet wheel. The engaging ends 34 of the tumblers are more or less pointed and 60 since they are arranged in the staggered relation above explained, it can be readily seen that at least one of the tumblers will partially engage one of the spaces 36 in any 65 position of the wheel, thereby enabling the sash to be locked against movement in either

direction in any position that it may assume.

Means are provided for holding the tumblers disengaged from the ratchet wheel when it is desired to move the sash. Arranged within the casing extension 28 is a lever 37 which is adapted to engage projections 38 and 39 formed on the tumblers. A 70 slideable rod 41 mounted in the frame and extending into the casing through an aperture 42 is arranged to engage the free end of the lever. By merely pressing the button 43 of the rod as will be clear from Figure 2 the lever will be moved to withdraw the tumblers from the ratchet against the action of 75 the springs 32 and 33.

In Figures 3 and 4 I have shown a slightly modified form of the tumblers as well as the means for retaining them against the ratchet and removing them therefrom. In this embodiment the tumblers are formed with legs 44 which are engaged by flat springs 32' and 33' and lever 37' in a manner substantially corresponding that of the somewhat equivalent members 32, 33 and 37 described in connection with the embodiment illustrated in Figures 1 and 2.

I claim:

1. In a device of the class described, a ratchet, and a plurality of tumblers adapted to simultaneously engage said ratchet and arranged whereby at least one tumbler when all are in said engagement may lie in one of the ratchet spaces in any of the positions of the ratchet with respect to the tumblers.

2. In a device of the character described in combination with spring actuated balancing means, a ratchet, a plurality of tumblers adapted to engage said ratchet simultaneously and arranged when so disposed whereby one tumbler will lie in staggered relation with respect to the ratchet spaces when another tumbler is seated therein, each of said tumblers when engaged in one of said spaces being capable of preventing the movement of the ratchet with respect to the tumblers in opposite directions, and means for holding all of said tumblers disengaged from said ratchet.

3. In a device of the class described in combination with spring actuated balancing means, a ratchet wheel, a plurality of tumblers adapted to engage said ratchet, resilient means tending to retain each of said tumblers in engagement with said ratchet, a lever arranged to eject each of said tumblers radially with respect to and from engagement with said ratchet wheel, and a reciprocatively mounted rod adapted to press against said lever for effecting said disengagement.

4. In a device of the character described in combination with spring actuated balancing means, a ratchet wheel, a plurality

of slidably mounted spring pressed tumblers adapted to engage said ratchet simultaneously, and means for simultaneously ejecting said tumblers from engagement with 5 said ratchet wheel.

5. In a device of the class described in combination with spring actuated balancing means, a ratchet wheel, a plurality of slidably mounted spring pressed tumblers 10 adapted to simultaneously engage said ratchet and arranged when so disposed whereby one tumbler will lie in staggered

relation with respect to the ratchet spaces when another tumbler is seated therein; a lever arranged to eject said tumblers from 15 engagement with ratchet, and means for moving said lever.

In testimony whereof, I have hereunto set my hand at Oakland, California, this 2nd day of November 1920.

ARTHUR C. WHEELOCK.

In presence of—
L. L. M. SALSBURY.
